Primary Examiner — Prabhakar Deshmukh(74) *Attorney, Agent, or Firm* — Edward E. Sowers;
Brannon Sowers & Cracraft PC(57) **CLAIM**

The ornamental design for a media player case, as shown and described herein.

DESCRIPTION

FIG. 1 is a top, front, right perspective view of a media player case showing my new design;

FIG. 2 is a bottom, rear, left perspective view thereof;

FIG. 3 is a top plan view thereof;

FIG. 4 is a front elevational view thereof;

FIG. 5 is a right side elevational view thereof;

FIG. 6 is a left side elevational view thereof;

FIG. 7 is a rear elevational view thereof; and,

FIG. 8 is a bottom plan view thereof.

The broken lines illustrate environment and form no part of the claimed design.
